(57) **CLAIM**

The ornamental design for a galloping front boot, as shown and described.

DESCRIPTION

FIG. 1 is a perspective view of a galloping front boot according to a first embodiment of the present invention;

FIG. 2 is a top plan view of a galloping front boot shown in FIG. 1;

FIG. 3 is a rear plan view of a galloping front boot shown in FIG. 1;

FIG. 4 is a front elevation view of a galloping front boot shown in FIG. 1;

FIG. 5 is a rear elevation view of a galloping front boot shown in FIG. 1;

FIG. 6 is a left side elevation view of a galloping front boot shown in FIG. 1;

FIG. 7 is a right side elevation view of a galloping front boot shown in FIG. 1;

FIG. 8 is a perspective view of a galloping front boot according to a second embodiment of the present invention.

FIG. 9 is a top plan view of a galloping front boot shown in FIG. 8;

FIG. 10 is a rear plan view of a galloping front boot shown in FIG. 8;

FIG. 11 is a front elevation view of a galloping front boot shown in FIG. 8;

FIG. 12 is a rear elevation view of a galloping front boot shown in FIG. 8;

FIG. 13 is a right side elevation view of a galloping front boot shown in FIG. 8; and,

FIG. 14 is a left side elevation view of a left galloping front boot shown in FIG. 8.
